UNITED STATES PATENT OFFICE.

ELIZABETH A. DAVIS, OF NEW YORK, N. Y., ASSIGNOR TO BLANCK & COMPANY, INC.,
OF NEW YORK, N. Y., A CORPORATION OF NEW YORK.

DESIGN FOR LACE.

56,802.

Specification for Design.

Patented Dec. 28, 1920.

Application filed October 7, 1920. Serial No. 415,459. Term of patent 3½ years.

To all whom it may concern:

Be it known that I, ELIZABETH A. DAVIS, a citizen of the United States, residing at New York, in the county of New York and State of New York, have invented a certain new, original, and ornamental Design for Lace, of which the following is a specification.

Said design consists in a lace pattern, as illustrated in the accompanying drawing, wherein the figure is a portion of a piece of lace showing my new design. The design repeats indefinitely on the net in accordance with the length of the piece of lace.

What I claim as new is:

The ornamental design for lace as herein shown and described.

In witness whereof, I have hereunto set my hand at New York, New York, this 5th day of October, A. D. nineteen hundred and twenty.

ELIZABETH A. DAVIS.
